UNITED STATES PATENT OFFICE.

THOMAS JAMES, OF SWANSEA, ENGLAND.

AUTOMATIC PLATE-CARRIER.

No. 867,977.

Specification of Letters Patent.

Patented Oct. 15, 1907.

Application filed August 20, 1906. Serial No. 331,839.

To all whom it may concern:

Be it known that I, THOMAS JAMES, a subject of the King of Great Britain and Ireland, and a resident of Vine House, Crown street, Morriston, in the county 5 borough of Swansea, Wales, have invented certain new and useful Improvements in Automatic Plate-Carriers for Use in the Manufacture of Tin and Terne Plates, for which I have obtained a patent in Great Britain, No. 16,967, bearing date 22d August, 1905, of which the 10 following is a specification.

This invention relates to an improved form of automatic carrier for use in the manufacture of tin and terne plates and has for its object to so construct and arrange such carrier that the plates are carried in a curved position from the finishing rolls to the branning machine without the intervention of manual labor or any chance of damaging the plates by the use of tongs or the like, so that by the use of an automatic carrier constructed, arranged and operating as hereinafter set forth half the 15 20 list which now exists in the present way of finishing coated plates is saved.

In carrying the said invention into effect, reference being had to the accompanying drawings which illustrate a carrier in plan Figure 1 and in sectional elevation Fig. 2, *a* represents a guide in which is adapted to work the finger *b* kept up to its work by the rolling weight *d* and *e* the guide frame for the same, said frame being attached to the grease pot casing in any suitable manner. The finger *b* at its rear end provided with a 25 30 slot *f* working over a suitable pin to limit the amount of travel and *g* represents a stationary guide or stud upon which said finger *b* works. To allow for the increase of the weight on the plates according to the thickness or number of plates to be treated I provide a slot *c* in the casing *a* in which a roller *c'* is free to work.

In working, the plates rise up vertically between the finishing rolls *x*, *x* in the grease pot *w* and strike on the underside of the back guides *h*, which may be of any desired curvature and which work in a horizontal 40 direction on the pivots *o* in the slotted bar *n* so that said plates are pressed forward, *i. e.* carried in a curved position so as to fall on the cradle arms *i* which are free to tilt and to permit the plates to slide in the direction of the branning machine, but before the plates fall on to

the arms *i*, which are mounted on bearings *j* on the 45 shaft *m*, they are caught at their lower end by the automatic finger or guide *b* which prevents them falling forward before the required time, the plates being held between the fingers *b*, guides *h* and the rear end of the cradle arms. Directly the plate has passed the fingers *b* the cradle arms *i* are depressed (weight of plates effecting this) and the plates shot into the branning machine, the arms *i* returning to their original position under the action of their counterweights *k*, amount of movement being limited by means of stops *l*. The 50 55 guides *h* are mounted in the slotted bar *n* in order that they may be adjusted to compensate for plates of different sizes.

Although only shown in the drawing as arranged for a three plate carrier yet it is to be understood that a 60 greater number may be used if necessary and that instead of carrying a series of separate plates one long plate may be carried at a time without departing in any way from the nature of the invention.

Having now described my invention, what I claim as 65 new and desire to secure by Letters Patent of the United States is:—

1. In combination, means for elevating plates, a carrier normally horizontal, a weight on the carrier to hold it in its normal position and means for guiding the plates to 70 the carrier.

2. In combination, means for elevating plates, a depressible carrier, means for limiting the movement of the carrier and means for guiding the plates to the carrier.

3. In combination, means for elevating plates, a guide, 75 a finger movable therein contacting with the plates and a weight movable in the guide contacting with the finger.

4. In combination, means for elevating plates, a guide having a slot, a finger movable in the guide and a roller mounted in the slots.

5. In combination, means for elevating plates, a guide having a slot, a finger movable in the guide and a roller mounted in the slots, said roller being above the finger.

6. In combination, means for elevating plates, a guide, a finger carried by the guide contacting with the plates and a stud carried by the guide on which the finger rests.

In testimony whereof I have affixed my signature in presence of two witnesses.

THOMAS JAMES.
